UNITED STATES PATENT OFFICE.

ADAM LANGE AND CARL LANGE, OF ST. LOUIS, MISSOURI.

DESIGN FOR SHOW-CASES.

Specification forming part of Design No. 7,508, dated June 30, 1874; application filed April 16, 1874.
[Term of Patent 7 years.]

To all whom it may concern:

Be it known that we, ADAM LANGE and CARL LANGE, both of St. Louis, in the county of St. Louis and State of Missouri, have invented a Design for Show-Cases, of which the following is a specification:

The nature of our design is fully represented in the accompanying drawing, to which reference is made.

Of said drawing, Figure 1 is a perspective view of our show-case. Fig. 2 is a transverse section at line *x x*.

A is the lower show-case; B, the top show-case. C is the frame bottom. As shown in the drawing, the show-case is illustrated so that its bottom case A, at front, is partly rounded, while the top case B is square shaped, hence their side frames *d d'* compose both shaped features.

In accordance with our design the glass panes D *d² d³ e² e³* correspond to complete the shape indicated.

The entire show-case is surrounded, in accordance with our design, by the usual panel strips *e c¹ c² c³ E e e'*, as shown in the drawing.

What we claim as our invention is—

A design in which the sides and front of the bottom case A are partly rounded, and the sides and front of the top case B are square shaped, as herein shown and described.

In testimony of said invention we have hereunto set our hands.

ADAM LANGE.
CARL LANGE.
